Letters Patent No. 66,962, dated July 23, 1867.

IMPROVED LIME-KILN.

The Schedule referred to in these Letters Patent and making part of the same.

TO ALL WHOM IT MAY CONCERN:

Be it known that I, SAMUEL C. HOTCHKISS, of Sylvania, in the county of Lucas, and State of Ohio, have invented a new and useful Improvement in Lime-Kilns; and I do hereby declare the following to be a full and correct description of the same, sufficient to enable others skilled in the art to which my invention appertains to understand and use the same, reference being had to the accompanying drawings, which make part of this specification, and in which—

Figures 1 and 2 are front and rear elevations of my improved lime-kiln.

Figure 3 is a vertical section of the same, in the line $x x$, fig. 4; and

Figure 4 is a horizontal section of the same, in line $y y$, figs. 1 and 3.

The nature of my invention consists in forming draught passages from the fire-places to the inner sides of the kiln, so that the fire may reach the lime on all sides, said passages not connecting with the outer air, and having an upward inclination. Also, in forming a draught passage at the bottom of my kiln in such a manner that a draught of cold air may be led through the hot, burnt lime, which air, in its passage through the same, will get heated, and, by carrying this heat upward to the stone that is burning, will help to create a draught through the middle of the kiln, and bring the greater heat to that part of the stone.

A, in the drawings, may represent a kiln, provided with two fire-places B and C, which consist of the common horizontal grates b and c , with ash-spaces below, and the vertical grates d and e on the inside of the kiln, which latter has the shape of a truncated cone, its widest part being where the grates are, and gradually diminishing in size upwards. The bottom is spherical, with a narrow vertical outlet, a , from which a draught passage, f , leads to the opening D, at which the burnt lime is taken out, the passage f being provided with a door, f' . From the fire-places B C lead draught passages $g g h h$, to the vertical grates i on the inner surface of the kiln, said passages inclining upwardly towards the grates i . E is an opening through which the stones are thrown into the kiln, and is provided with a door, e' . The kiln is filled with limestone to its capacity, care being taken, as is usual, to place the larger stones in the middle and the smaller ones around them, so as to prevent their jamming as they fall down. The door e is then closed, and the fires kindled in the fire-places B and C. After a sufficient quantity of lime has been burnt, the stones below the fire which are not burnt are withdrawn through the opening D, when the burnt lime falls to the bottom, and the stones above which have not yet been burnt take its place at the fire, and the kiln is filled again. The upwardly-inclined passages g and h create a draught which draws the fire through the same to the grates i , so that the stone is subjected to the flames on all sides. Were the passages $g h$ horizontal, but a very poor draught would be created, but their upward inclination creates a powerful one; and if these passages were connected with the outer air, a current of cold air would be forced on the flames, which would take away a great deal of the heat saved by my improvement and would deaden the fires in the fire-places. It is well known that the stones in the centre of the kiln are the hardest to burn, as the flames have a tendency to burn on the sides of the same and consume the smaller stones. To obviate this, I create a central draught through the passage f and outlet a , which ascending through the burnt lime, which is still at a white heat, and in cooling the same, carries the heat in a powerful blast directly up the centre of the kiln, drawing at the same time the flames from the grates d , e , and i towards the centre, and thus burn the limestones equally in the centre and on the sides. The draught through the passage f is regulated by the door f' . The fire-places or arches and the ash-places are provided with doors, the former of which have holes, so that the door may be closed and still a draught kept up.

Having thus described my invention, what I claim as new, and desire to secure by Letters Patent, is—

1. In a lime-kiln, the upwardly-inclining draught passages $g g h h$, substantially as and for the purposes described.

3. The combination of the upwardly-inclining passages $g g h h$ with the outlet a and draught passage f , substantially as for the purposes described.

S. C. HOTCHKISS.
